[57] CLAIM

The ornamental design for a medication carrier insert, as shown and described.

DESCRIPTION

FIG. 1 is a top plan view of a medication carrier insert, showing my new design;

FIG. 2 is an end elevational view of FIG. 1;

FIG. 3 is an underside view of FIG. 1;

FIG. 4 is a side elevational view of FIG. 1;

FIG. 5 is a fragmentary top plan view of an alternate embodiment, wherein the only difference resides in the shape of the individual pill carriers;

FIG. 6 is an end elevational view of FIG. 5;

FIG. 7 is an underside view of FIG. 5;

FIG. 8 is a side elevational view of FIG. 5;

FIG. 9 is a top plan view of a further modified embodiment of the design;

FIG. 10 is an underside view of FIG. 9;

FIG. 11 is a side elevational view of FIG. 9;

FIG. 12 is an end elevational view of FIG. 9.
